FIRE BOX FOR BOILERS

Chester A. Siegel, Newark, N. J., assignor to
 American Arch Company, New York, N. Y., a
 corporation of Delaware

Continuation of application Serial No. 649,836,
 January 3, 1933. This application June 15,
 1934, Serial No. 730,709

12 Claims. (Cl. 122—68)

This application is a continuing application with respect to my copending application Serial No. 649,836, filed on January 3, 1933, and relates back to said application Serial No. 649,836 for all dates and rights incident to the filing thereof.

The present invention relates to fireboxes for boilers and has particular reference to the internal fireboxes of boilers of the so-called locomotive type.

10 The general object of the invention is to provide improved water steaming and circulating structure of the general kind disclosed in Patent No. 1,894,613, granted to me January 17, 1933, in combination with firebox sheet structure of improved form whereby to provide for expansion and contraction of the firebox crown sheet and side sheets longitudinally of the firebox, and to provide for expansion and contraction of the water steaming and circulating structure.

20 Other and more detailed objects of the invention and the advantages to be derived from its use will become apparent from a consideration of the ensuing description of a preferred form of apparatus embodying the invention, which is illustrated in the accompanying drawings in which:

Fig. 1 is a vertical longitudinal section of part of a locomotive boiler having a firebox embodying the invention;

25 Fig. 2 is a section taken on the line 2—2 of Fig. 1;

Fig. 3 is a detail of part of the structure shown in Figs. 1 and 2;

30 Fig. 4 is a perspective view of water steaming and circulating structure embodying the invention; and

Fig. 5 is a perspective view of a portion of the firebox inner sheet showing an opening therein adapted to receive the structure illustrated in Fig. 4.

40 Referring now to Figs. 1 and 2, the boiler is indicated generally at 10, and is provided with a firebox 12 formed by inner firebox sheet structure comprising a crown sheet 14 and inner side sheets 16. An outer wrapper sheet 18, stayed to the inner firebox sheet structure by means of the usual staybolts 20, provides, with the inner sheet structure, the usual side water legs 22 and a crown space 24 above the crown sheet. The wrapper sheet 18 and the side sheets 16 are joined at the bottom of the firebox by the usual mud ring 26.

45 The front end is extended to form a combustion chamber 28, which at its forward end terminates in the rear flue sheet 30, into which are rolled the boiler flues 32. At the rear of the firebox

there is provided the usual back head 34, defined by the inner and outer back head sheets 36 and 38. At 40 there is provided the usual firing door.

5 In the embodiment illustrated the firebox is provided with a plurality of transverse hollow water steaming and circulating members indicated generally at A. These members serve to connect the side sheet structure of the firebox with the crown sheet, but instead of being connected directly to plane portions of the side 10 sheets and crown sheet, they are connected to inwardly bulged portions of this sheet structure, which provide for longitudinal expansion and contraction of the inner firebox sheets.

As shown in Fig. 5, the inner firebox sheet 15 forming the crown and side sheets is cut away to provide an opening 42 extending transversely across the crown sheet 14 and downwardly of the side sheets 16 to a zone adjacent the lower portion of the firebox. As many openings 42 are 20 provided as there are circulators A. The circulator structure, adapted to close each opening 42, comprises a sheet 44 bent in a generally U-shaped form and adapted to be sealed at its edges as by welds 45 to the edges of opening 42 in the 25 firebox sheet structure. The sheet 44 is inwardly bulged as at 46 to provide a ridge extending longitudinally of the sheet 44 for substantially the full length of the legs 48 of the sheet 44 and across the intermediate portion of the sheet 44 connecting the legs of the U-shaped portion.

30 Each circulator A, in the embodiment illustrated, is of generally T-shaped form having arms 50 connected at their ends to suitable openings 52 in the inwardly bulged parts of the legs 48 of sheet 44. Preferably these connections are made by welding, as shown at 54 in Figs. 2 and 3. The stem 56 of the circulator A connects the arms 50 with an opening 58 in the inwardly bulged part of the intermediate portion of sheet 44, the 40 connection preferably being made by means of a weld 60 around the edge of the opening 58. As will be evident from the drawings, the arms 50 are generally tubular in form, and the arms of adjacent circulators serve to support between 45 them a plurality of refractory arch brick or tile 62, which, together with arch refractories 64, the forward ends of which advantageously rest on the throat sheet 66, serve to provide a firebox arch.

45 The upper portion of the stem of each circulator is, in the embodiment illustrated, flattened to generally oval form, and the flat sheets of the stem are stayed by means of staybolts 68.

50 Insofar as the present invention is concerned, the specific shape of the T-shaped circulator mem- 55

bers A may vary considerably, as also may the manner of fabricating these members. In fabricating the structure, however, I prefer to form and weld together the several parts making up the structure shown in Fig. 4, after which this structure is advantageously inserted as a unit into the opening 42 of the firebox sheet structure and welded thereto. Obviously, if desired however, the sheet 44 can be welded in place to the inner firebox sheet and the circulator thereafter welded to the sheet 44.

It will be apparent from the drawings that the inwardly bulged portions or ridges 46 provide resilience in longitudinal direction for taking up expansion and contraction in this direction of both the side and crown sheets of the firebox, and these inwardly bulged ridges also provide for a certain degree of resilience permitting the expansion of the circulators both transversely of the firebox and vertically thereof to be taken up without unduly stressing the firebox sheet structure.

The number and arrangement of the circulators may vary within the scope of the invention depending upon the specific character of the firebox and the kind of arch desired, and as shown in my previously mentioned application Serial No. 649,836, the side water leg spaces 22 of the firebox may be divided by vertical baffle members 30 extending downwardly of the water legs and terminating somewhat above the level of the mud ring 26.

While in accordance with the patent statutes, I have disclosed a preferred embodiment of my invention, it is to be understood that changes and modifications of the structure herein disclosed may be made without departing from the spirit or scope of the invention as defined in the appended claims, and it is further to be understood that certain features of the invention may be employed to the exclusion of others.

What I claim is:

1. In a boiler, a firebox having crown sheet and inner and outer side sheet structure defining side water legs below the level of the crown sheet, said crown and inner side sheet structure comprising a plurality of longitudinally spaced inwardly bulged portions extending transversely of the crown sheet and downwardly of the side sheets, said portions being freely flexible longitudinally of the firebox to provide for longitudinal expansion and contraction of the crown and inner side sheets and a plurality of hollow water steaming and circulating members located transversely of the firebox, each of said members connecting the crown sheet part of one of said inwardly bulged portions with the side sheet parts of the same inwardly bulged portion at opposite sides of the firebox.

2. In a boiler, a firebox sheet structure comprising a crown sheet and side sheets, said side sheets having a plurality of inwardly bulged portions freely flexible longitudinally of the firebox and extending in generally vertical direction and spaced longitudinally of the firebox whereby to permit longitudinal expansion and contraction of the side sheets and a plurality of water steaming and circulating members having hollow lower portions bridging the firebox between said bulged portions of the side sheets and hollow portions connecting said lower portions with said crown sheet.

3. In a boiler, a firebox sheet structure comprising a crown sheet and side sheets, said crown sheet having a plurality of inwardly bulged portions freely flexible longitudinally of the firebox

and extending transversely thereof and spaced longitudinally of the firebox whereby to permit longitudinal expansion and contraction of the crown sheet, and a plurality of water steaming and circulating members having hollow upper portions depending into the firebox from said inwardly bulged portions and hollow lower portions bridging the firebox between said side sheets and connected to the lower ends of the first-mentioned hollow portions.

4. In a boiler, a firebox having a crown sheet and inner and outer side sheets defining side water legs extending below the level of the crown sheet, said crown sheet and said inner side sheets being cut away to provide an opening extending transversely of the crown sheet and downwardly of the inner side sheets and a water steaming and circulating member extending transversely of the firebox, the said member comprising a hollow portion bridging the firebox and a hollow portion extending upwardly from said first named portion and communicating with the space above the crown sheet and a portion closing the opening in said sheets, said last named portion being bulged inwardly of the firebox and freely flexible longitudinally thereof to provide a yielding connection between the portions of the crown sheet and the inner side sheets on the opposite sides of said opening, whereby to permit longitudinal expansion and contraction of said crown sheet and said inner side sheets.

5. In a boiler, a firebox having crown sheet and inner and outer side sheet structure defining side water legs extending below the level of the crown sheet, said inner side sheet structure comprising substantially vertically extending inwardly bulged portions providing for longitudinal expansion and contraction of the side sheets, and a water steaming and circulating member comprising a lower hollow portion bridging the firebox and a hollow portion extending upwardly from the lower portion and communicating with the space above the crown sheet, the ends of said lower portion joining the inner side sheet structure at opposite inwardly bulged portions thereof.

6. In a boiler, a firebox having crown sheet and inner and outer side sheet structure defining side water legs extending below the level of the crown sheet, said crown and inner side sheet structure comprising an inwardly bulged portion extending transversely of the crown sheet and downwardly of the side sheets, said portion being freely flexible longitudinally of the firebox to provide for longitudinal expansion and contraction of the crown and inner side sheets and a water steaming and circulating member comprising a hollow lower portion bridging the firebox and a hollow portion extending upwardly from the lower portion and communicating with the space above the crown sheet, the ends of said lower portion joining the inner side sheet structure at opposite inwardly bulged portions thereof and the inwardly extending portion joining the inwardly bulged portion of the crown sheet structure.

7. Circulator structure for boiler fireboxes having crown and side sheets, comprising a generally U-shaped portion having an inwardly bulged ridge extending longitudinally thereof, said U-shaped portion being adapted to be sealed to the edges of an opening extending transversely of the crown sheet and downwardly of the side sheets and a hollow portion comprising a part connecting openings in said ridge in the legs of said U-shaped portion and a part connecting the first-mentioned part with an opening in said ridge in

the part of said U-shaped portion connecting said legs.

8. Circulator structure for boiler fireboxes having crown and side sheets, comprising a generally U-shaped portion having an inwardly bulged ridge extending longitudinally thereof, said U-shaped portion being adapted to be sealed to the edges of an opening extending transversely of the crown sheet and downwardly of the side sheets and a hollow and generally T-shaped portion having arms connecting openings in said ridge in the legs of said U-shaped portion and a stem connecting said arms with an opening in said ridge in the part of said U-shaped portion connecting said legs.

9. Circulator structure for boiler fireboxes having crown and side sheets comprising a generally U-shaped portion having inwardly bulged ridges extending longitudinally of the legs thereof, said ridges being freely flexible laterally thereof, said portion being adapted to be sealed to the edges of an opening extending transversely of the crown sheet and downwardly of the side sheets, and a hollow portion connecting openings in said ridges with an opening in the part of said U-shaped portion connecting said legs.

10. Circulator structure for boiler fireboxes having crown and side sheets comprising a generally U-shaped portion having an inwardly bulged ridge extending longitudinally of the intermediate part of said U-shaped portion, said portion being adapted to be sealed to the edges of an opening

extending transversely of the crown sheet and downwardly of the side sheets, and a hollow portion connecting an opening in said ridge with openings in the legs of said U-shaped portion.

11. Circulatory structure for boiler fireboxes having crown and side sheets, comprising a generally U-shaped portion having a freely flexible and unstayed inwardly bulged ridge extending longitudinally thereof, said U-shaped portion being adapted to be sealed to the edges of an opening extending transversely of the crown sheet and downwardly of the side sheets, and a hollow portion comprising a part connecting openings in said ridge in the legs of said U-shaped portion and a part connecting the first-mentioned part with an opening in said ridge in the part of said U-shaped portion connecting said legs.

12. Circulatory structure for boiler fireboxes having crown and side sheets, comprising a generally U-shaped portion having a relatively wide and shallow and freely flexible inwardly bulged ridge extending longitudinally thereof, said U-shaped portion being adapted to be sealed to the edges of an opening extending transversely of the crown sheet and downwardly of the side sheets, and a hollow portion comprising a part connecting openings in said ridge in the legs of said U-shaped portion and a part connecting the first-mentioned part with an opening in said ridge in the part of said U-shaped portion connecting said legs.

CHESTER A. SIEGEL.
